US0D1099296S

(12) **United States Design Patent** (10) **Patent No.:** **US D1,099,296 S**
(45) **Date of Patent:** **** Oct. 21, 2025**

(54) **FLUID CONTROL DEVICE**

(71) Applicant: **Magnolia Medical Technologies, Inc.**,
Seattle, WA (US)

(72) Inventor: **Jay M. Miazga**, Langley, WA (US)

(73) Assignee: **Magnolia Medical Technologies, Inc.**,
Seattle, WA (US)

(**) Term: **15 Years**

(21) Appl. No.: **29/783,991**

(22) Filed: **May 17, 2021**

(57) **CLAIM**

The ornamental design for a fluid control device, as shown and described.

DESCRIPTION

FIG. 1 is a perspective view of a seventh embodiment of the fluid control device;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines immediately adjacent the shaded areas represent the bounds of the claimed design while all other broken lines are directed to environment and are for illustrative purposes only; the broken lines form no part of the claimed design.

1 Claim, 7 Drawing Sheets
